STEAM GENERATING AND SUPERHEATING UNIT WITH FIXED JET BLOWERS DIRECTED AT SUPERHEATER PLATENS

Ralph M. Hardgrove, North Canton, Ohio, assignor to The Babcock & Wilcox Company, New York, N.Y., a corporation of New Jersey

Filed Nov. 16, 1955, Ser. No. 547,193

3 Claims. (Cl. 122—392)

This invention relates to fixed jet air blowers for removing accumulations such as the stalactites of slag depending from the ends of the spaced platens of a superheater disposed within the upper part of a furnace chamber, the furnace having associated therewith means for burning a slag forming fuel which, in the operation of the associated steam generating and superheating unit, results in the accumulations upon the ends of the platens nearest the fuel burning means in the form of stalactites, which are most difficult to remove.

In spite of numerous suggestions which may have been made with reference to slag removal from such fluid heating tubular units disposed in the path of high temperature furnace gases carrying slag particles in suspension, it has been one of the most difficult and vexing problems in the art of high pressure steam generation and superheating to maintain superheater platens in a sufficiently high gas temperature zone to attain steam superheat temperatures of the order of 1100 degrees F., and keep them in operative condition, because of the slag accumulations upon the portions of the superheater components nearest the fuel burning means. The superheater platens have been spaced apart widely enough to prevent the slag bridging between successive platens, but the slag accumulations still persist to such an extent that they interfere with effective heat transfer and efficient operation of the unit, even when frequent lancing is practiced.

This invention solves this problem by providing fixed jet air blowers, each directed against the extreme lower part of a tubular superheater component most subject to slag accumulation in the operation of the unit.

The invention will be set forth in concise manner in the appended claims, but for a more complete understanding of the invention, its uses, and advantages, recourse should be had to the following description which refers to the accompanying drawings in which a preferred embodiment of the invention is shown.

In the drawings:

Fig. 1 is a vertical section or sectional side elevation showing the arrangement of the fixed air jet air blowers with reference to the superheater platens;

Fig. 2 is a partial plan or horizontal section upon the line 2—2 of Fig. 1;

Fig. 3 is a detailed horizontal section of one of the fixed jet air blowers showing its association with adjacent tubes of the furnace wall, taken on the line 3—3 of Fig. 4;

Fig. 4 is a fragmentary vertical section of the elements of Fig. 3;

Fig. 5 is a fragmentary plan or horizontal section taken upon the plane of the line 5—5 of Fig. 1; and

Fig. 6 is a fragmentary horizontal section illustrating a few of the tubes of a superheater platen in association with a horizontal fluid conducting platen spacer tube constructed and arranged to maintain the superheater platens in their operative relationships.

Fig. 1 of the drawing illustrates a steam generating

2

unit having a cyclone furnace 10 burning particle form solid fuel having slag forming characteristics, and operating at temperatures above the fusion temperature of the incombustible in the fuel. The illustrative cyclone furnace fired unit is of the type shown in the patent to Kerr et al. 2,594,312. Crushed coal, in particle form, is fed to the cyclone furnace 10 through the fuel burning means 12 and combustion supporting air is simultaneously delivered to the furnace 10 through the tangentially directed opening 14 to burn the fuel at the pertinent high temperature within the furnace. During operation of the furnace molten slag flows from the lower part thereof through the openings 16 while the combustion gases flow from the cyclone furnace through its throat 18 into the primary furnace chamber 20. The molten slag continues to flow along the bottom of the primary furnace chamber and then through the slag exit opening 22 into the slag pit 24.

The high temperature combustion gases from the primary furnace chamber 20 flow upwardly across the steam generating screen tubes 26, appropriately connected into the fluid circulation of the unit, such connections including lower connections to the submerged drum 28, and upper connections to the steam and water drum 30, as illustrated in Fig. 1.

The high temperature furnace gases with particles of fused slag suspended therein pass upwardly from the tubular screen 26 through the lower part 32 of the secondary furnace chamber where they contact the lower ends of spaced superheater platens 34 and 36, which are widely spaced across the flow of gases and connected to receive steam from the steam and water drum 30 in a manner specifically shown in the pending application Serial No. 336,525, now Patent No. 2,834,324 filed in the name of G. J. Schoessow, on February 12, 1953 and belonging to the same assignee. The disclosure of this application also involves the details of the means for holding the spaced superheater platens in their operative relationships, such means involving the platen spacing tubes indicated at 40 and 42 in Fig. 5. These tubes pass through the platens as indicated in Figs. 1 and 6 and have welded thereon projecting lugs such as 44—47 (Fig. 6) arranged on opposite sides of the tubes of a superheater platen 36. Fig. 6 indicates four tubes 36A, 36B, 36' and 36'' of a platen 36 with the platen tube 36' having secured thereto lugs 50 and 51, which co-act with the associated lugs 44 and 45, on the platen spacing tube 42 in a manner similar to which the lugs 54 and 56 on the tube 36'' co-act with the platen spacer tube lugs 46 and 47. This arrangement of elements permits the platens to expand or contract relative to the spacer tubes 40 and 42, while the superheater platens are still maintained in their operative spaced relationship.

The superheater platens are disposed in the gas flow in the upper part of the furnace chamber, the rear wall of which is common to that furnace chamber and a downflow convection gas pass 60, in which other components of the convection heating apparatus of the unit are disposed. Such components are indicated at 62—64, as convection superheater sections involving banks of horizontally extending and vertically spaced superheater tubes disposed transversely of the downflow of gases within the gas pass 60.

The wall 76 separating the upper part of the secondary furnace chamber 32 from the downflow gas pass 60 extends to the flue or exit 80 of the downflow gas pass from the gas exit 78 of the furnace chamber. At the position of this exit the gases flow to the right from the top of the furnace chamber 32, and to the top of the downflow gas pass 60.

Fig. 1 indicates the steam generating tubes of the wall 76 as extending from the submerged drum or header 28

as indicated at 90—92. Thence, some of these tubes extend upwardly along the wall 94 below the gas exit 80 of the downflow pass 60, and above this position all of the tubes join in forming the main part of the wall 76. At the upper end of this wall, the tubes are more widely spaced and arranged in screen formation across the gas exit of the furnace chamber 32.

At the level indicated by the numeral 70 in Fig. 1 the tubes of the wall 76, or some of them, are bent out of their wall forming alignment indicated at 96 in Fig. 2. Such bent out portions are indicated at 98 and 101 in Fig. 2. At the positions in which the tubes are bent out of their wall forming alignment in this manner there are fixed jet air blowers 104. Each of these jets has a tube such as that indicated at 106 in Fig. 3, with a tapered end providing the nozzle 108, the exit end of which is welded to the wall tubes 100 and 99 as indicated at 110 and 112. The upper and lower walls 114 and 116 (Fig. 4) of each nozzle are welded as indicated at 118 and 120 to flat intertube studs, such as 122 and 124 which, in turn, are welded to the tubes. Thus, each jet is held in such a position that the stream of high velocity air directed from the nozzle is aimed at one of the platens 36, and at a position at the extreme lower end of the platen, as clearly indicated in Fig. 1.

It is to be understood that there is one of the fixed jet air blowers with its nozzle arranged in the above described manner for each of the platens 34 and 36. The blowers 130 extend through the front wall 132 of the unit at the level 72 in the manner indicated in Fig. 2 and are directed against the extreme lower end of the platens 34 as indicated in Fig. 1. The nozzles of blowers 130 are arranged with reference to the wall tubes 136 of the front wall of the steam generating unit in a manner similar to that above described with reference to the tubes of the wall 76.

The above described fixed jet air blowers may lead from headers, such as the headers 140 and 142 from which appropriate conduits lead through the valves 144 and 146 to the tubular portions 106 of the jets.

The illustrative steam generating and superheating unit is rectangular in cross-section, having its pressure part heat absorbing tubular components enclosed by walls and other enclosure portions, including the rear wall 170, the roof 172, the primary furnace chamber floor 174 and the inclined wall 176 of the lower part of the furnace chamber 32, these enclosure portions including heat insulating material, as is well understood in this art.

It is also to be understood that the walls of the cyclone furnace 10 involve heat resisting refractory and exteriorly arranged heat insulating material in conjunction with steam generating tubes generally semi-circular, and leading from the lower header 180 to the upper header 182 which may be appropriately connected into the fluid circulation of the unit as above indicated in greater detail in the co-pending application and the patent identified above, and belonging to the same assignee.

Some of the pressure parts of the unit are disposed above the roof 200 of the furnace chamber 32, and the downflow gas pass 60, the enclosure for these pressure parts including the roof 172 and the front wall section 202 in combination with part of the side wall 204 (Fig. 2) of the unit.

Fig. 5 indicates groups 210 of the upper parts of the tubes of the wall 76, which are arranged in the manner here shown for the purpose of reducing gas flow resistance through the unit.

Whereas the invention has been described with reference to a preferred embodiment indicated in the drawings, it is to be recognized that the invention is not to be regarded as limited to all of the details disclosed and described. It is rather to be considered as a scope commensurate with the scope of the subjoined claims.

What is claimed is:

1. A fluid heating unit comprising front, side and rear

walls defining a vertically elongated housing having a furnace chamber in the lower part and a vertical upflow gas pass in the upper part thereof, means for burning a slag-forming solid fuel at temperatures above the slag fusion temperature in said furnace chamber, vertically arranged fluid heating tubes lining said front wall, a plurality of groups of nested U-shaped fluid heating tubes in said upflow gas pass arranged to form a row of transversely spaced top supported pendant radiantly heated tube platens arranged in parallel vertical planes normal to said front wall and in position to have their looped lower end portions impacted by slag-laden high temperature gases from said furnace chamber, a series of fluid jet nozzles fixedly positioned in said front wall at transversely spaced positions therein, and each of said fluid jet nozzles having its discharge end positioned between and terminating in heat transfer contact with a pair of fluid heating tubes lining said front wall and arranged to discharge a fluid jet in the plane of a corresponding tube platen and directed at the lower end thereof to clear said tube platen of slag depositing on the lower end thereof.

2. A fluid heating unit comprising front, side and rear walls defining a vertically elongated housing having a furnace chamber in the lower part thereof, means for burning a slag-forming solid fuel at temperatures above the slag fusion temperature in said furnace chamber, a vertically extending baffle extending between said side walls and intermediate said front and rear walls and co-operating therewith to define a vertical upflow gas pass opening at its lower end to said furnace chamber and an adjoining serially connected vertical downflow gas pass, vertically arranged fluid heating tubes lining said front wall and baffle, a plurality of groups of nested U-shaped fluid heating tubes in said upflow gas pass arranged to form a row of transversely spaced top-supported pendant radiantly heated tube platens arranged in parallel vertical planes normal to said front wall and said baffle and in position to have their looped lower end portions impacted by slag-laden high temperature gases from said furnace chamber, a series of fluid jet nozzles fixedly positioned in said front wall at transversely spaced positions therein, a second series of oppositely arranged fluid jet nozzles mounted on said baffle at transversely spaced positions therein, and each of said fluid jet nozzles in said first and second series having its discharge end positioned between and terminating adjacent to a pair of fluid heating tubes in said front wall and baffle respectively and arranged to discharge a fluid jet in the plane of a corresponding tube platen and directed at the lower end thereof to clear said tube platen of slag depositing on the lower end thereof.

3. A fluid heating unit comprising front, side and rear walls defining a vertically elongated housing having a furnace chamber in the lower part thereof, means for burning a slag forming solid fuel at temperatures above the slag fusion temperature in said furnace chamber, a vertically extending baffle extending between said side walls and intermediate said front and rear walls and co-operating therewith to define a vertical upflow gas pass opening at its lower end to said furnace chamber and an adjoining serially connected vertical downflow gas pass, vertically arranged fluid heating tubes lining said front wall and baffle, a plurality of groups of closely spaced nested U-shaped fluid heating tubes in said upflow gas pass arranged to form front and rear rows of transversely spaced top-supported pendant radiantly heated tube platens arranged in parallel vertical planes normal to said front wall and said baffle and in position to have their looped lower end portions impacted by slag-laden high temperature gases from said furnace chamber, means for holding the tube platens in each row in transversely spaced relation, a series of fluid jet nozzles fixedly positioned in said front wall at transversely spaced positions therein, a second series of oppositely arranged fluid jet nozzles mounted on said baffle at transversely spaced posi-

tions therein, and each of said fluid jet nozzles in said first and second series having its discharge end positioned between and terminating adjacent to a pair of fluid heating tubes in said front wall and baffle respectively in heat transfer contact therewith and arranged to discharge a 5 fluid jet in the plane of a corresponding tube platen and directed at the lower end thereof to clear said tube platen of slag depositing on the lower end thereof.
